ROBERT S. NOAH, OF ANNAPOLIS, MARYLAND, ASSIGNOR TO HENRY B. REINHARDT,
TRUSTEE, OF ROLAND PARK, MARYLAND.

DISAPPEARING TOWER FOR SUBMARINES.

1,296,689.

Specification of Letters Patent. Patented Mar. 11, 1919.

Application filed December 13, 1916. Serial No. 136,792.

To all whom it may concern:

Be it known that I, ROBERT S. NOAH, a citizen of the United States, residing at Annapolis, in the county of Anne Arundel and 5 State of Maryland, have invented certain new and useful Improvements in Disappearing Towers for Submarines, of which the following is a specification.

This invention relates to improvements in 10 sea-going vessels of the submersible or submarine type, and has particular reference to providing such vessels with one or more towers movable upwardly above the deck.

Such a tower will be a substitute for the 15 ordinary conning tower now used and may be constructed to serve various purposes each of which will increase the efficiency of submarines.

The present invention shows the inventive 20 idea in the form of a tower that will enable several persons who are aboard the submersible to be elevated at the same time, without raising the vessel itself, in order to bring the eyesight of such persons above the 25 sea-level and afford all the persons a view of any vessels that may be afloat in that vicinity.

The new form of vertically-movable tower 30 may also be used to effect an air-ventilation of the submarine vessel without raising the vessel to the surface so that its upper deck shall be exposed above the water's surface.

The invention is illustrated in the annexed drawing, in which is shown a vertical section 35 of a portion of a submarine hull.

Referring now to the drawing by designating numerals, 6, designates the exterior bottom of the hull; on top at the highest part of the hull is an upper deck, 9, and next 40 below is a ceiling, 11, and the space between said upper deck, 9, and the ceiling, 11, constitutes an air-chamber, 10, formed within the top of the hull.

The lowermost deck, 19, is also the floor 45 of the engine room, and an intermediate deck, 18, which is the ceiling of the engine room separates the lower compartments, 16, from the upper compartments, 17; between the lower deck, 19, and the bottom, 6, of the 50 hull is the space, 20, for ballast water, and for the reception of sea-water that is required to cause the vessel to submerge. Of course the bulkheads, decks, and other ordinary interior construction of the hull, may

be planned by the constructor in any different way from that here shown. 55

Coming now to describe one form of the embodied invention, a vertical cylinder, 12, of any preferred construction is provided, and the same has fixed position within the 60 hull and extends through the decks of the submarine vessel. This cylinder has a closed lower end, 13, and its upper end 14, and the packing seat, 29, in the upper end, in the present instance, is flush with the top of the 65 upper deck.

The circular wall of the cylinder has openings, 21, 22, which may communicate with lower and upper compartments, 16, and 17, respectively; doors, 23 are provided to close 70 said cylinder openings.

A hollow circular tower, 24, fits like a piston movably within said vertical cylinder, 12, and this tower is provided on its exterior with circumferential packing rings, 25, that 75 contact with the inner surface of said cylinder. The hollow movable tower, 24, has a closed bottom, 26, and a closed top, 27, and a flange, 28, around the top projects horizontally and when this tower is in the lowered position, as shown in the drawing, said top flange, 28, contacts with the packing seat, 29, positioned at the top end of the cylinder. The packing seat, 29, and the flange, 28, pressing down upon it makes a tight 80 joint that excludes sea-water. 85

It will be understood that when the tower 24, has this down position in the hull it will have disappeared from the view of any person afloat on any vessel that may be in the 90 vicinity of this submarine.

The broken line, 88, extending horizontally, indicates the position of the surface of the sea-water, when the vessel is afloat.

The vertically-movable tower, 24, is provided in its wall with doors, 30 and 31, which coincide with the doors, 23, in the wall of the cylinder, 12, when the tower is down. A floor, 32, is approximately in the middle of the vertically-movable tower, and 95 forms a lower and an upper chamber, 33 and 34, each high enough to permit an ordinary man to stand upright therein. A ladder, 35, may be carried in the lower chamber and the same extends to the floor, 100 32, of the upper chamber, and this ladder enables persons who enter the lower chamber to ascend to the upper chamber. When 105

the tower is raised the position its upper part takes is indicated by broken lines. It will be understood that persons in the upper chamber, 34, of the tower when the latter is raised will be at an elevation entirely above the hull and the top deck, 9, of the submarine during the time the tower occupies the raised position, and that such elevation of the tower will afford those persons a range of observation that has not been obtainable on submarines as heretofore constructed.

The upper chamber of this upwardly-movable tower may also carry a periscope. 15 Means are here shown for raising the tower, 24, from its down position to its elevated position. One form of means is to employ fluid pressure.

A pump, 37, rests on the lower deck, 19, 20 and at each of two opposite sides of the pump is an attached pipe, one of which is designated, 38, and the other, 39; these two pipes pass through the lower deck 19 and open into the storage-water, or bilge-water, 25 space, 20. Each of these pipes has a cut-off valve, 40. Attached also to opposite sides of the pump, 37, is a pipe designated at one side 41, and at the other side designated, 42. These last named pipes pass through the 30 lower deck and extend along the water space, 20, and then pass upward through the bottom, 13, of the cylinder below the closed lower end, 45, of the movable piston 24. Each pipe of the two last named has 35 a cut-off valve, 43. By manually operating the several cut-off valves the piston, turret and gun may be raised or lowered by the pump 37.

Having described my invention what I claim and desire to secure by United States 40 Letters Patent is,—

A submarine vessel having a hull provided with an inclosed uppermost deck, an inclosed lowermost deck, and an inclosed intermediate deck which form lower and upper compartments; a hollow vertical cylinder in fixed position and extending from the lowermost deck up through the intermediate deck and with its upper open end of the cylinder flush with the top surface of the 50 upper deck—the walls of this cylinder being provided with a door-opening communicating into said lower compartment and a second door-opening communicating into said upper compartment; and a hollow cylindric tower movable like a piston within said fixed cylinder and the walls of the movable tower having two door-openings and doors which are positioned relatively to the 55 said two door-openings in the fixed cylinder so as to coincide with the latter when the movable tower has its disappeared position, and when the movable tower has its elevated position one of its said door-openings will coincide with the door-opening in the fixed cylinder that communicates with said upper compartment while the other door-opening of the tower at the same time will be above the upper deck and exposed to the atmosphere. 60

In testimony whereof I affix my signature in the presence of two witnesses:

ROBERT S. NOAH.

Witnesses:

LOUIS C. KLERLEIN,
IZELLA E. BAGLEY.
